CLAIM

The ornamental design for a handle for shaver, as shown and described.

DESCRIPTION

FIG. 1 is a perspective view of a first embodiment showing a handle for shaver according to my design;

FIG. 2 is a front elevational view thereof;

FIG. 3 is a rear elevational view thereof;

FIG. 4 is a right side elevational view thereof;

FIG. 5 is a left side elevational view thereof;

FIG. 6 is a top plan view thereof;

FIG. 7 is a bottom plan view thereof;

FIG. 8 is a perspective view of a second embodiment showing a handle for shaver according to my design;

FIG. 9 is a front elevational view thereof;

FIG. 10 is a rear elevational view thereof;

FIG. 11 is a right side elevational view thereof;

FIG. 12 is a left side elevational view thereof;

FIG. 13 is a top plan view thereof; and,

FIG. 14 is a bottom plan view thereof.

The portions of the handle for shaver shown in broken lines are included for the purpose of illustrating unclaimed portions of the handle for shaver and form no part of the claimed design.
